UNITED STATES PATENT OFFICE.

EUGENE BEEBE, JOHN M. CONNOR, AND EUGENE BEEBE, JR., OF MONTGOMERY, ALABAMA.

THILL-COUPING.

SPECIFICATION forming part of Letters Patent No. 228,506, dated June 8, 1880.

Application filed April 8, 1880. (No model.)

To all whom it may concern:

Be it known that we, EUGENE BEEBE, JOHN M. CONNOR, and EUGENE BEEBE, Jr., of Montgomery, Alabama, have invented a new and useful Shaft and Pole Coupling, of which the following is a specification.

Our invention relates to improvements in thill-couplings; and the objects of our improvements are, first, to provide a perfect anti-rattling connection; second, to provide a device that, in case the shaft or pole of a vehicle or the harness should break, the shaft or pole will be held in a horizontal position, and not by falling strike or become entangled with the legs of the draft-animal.

15 We attain these objects by means of the devices hereinafter described, and illustrated in the accompanying drawings, in which—

Figure 1 is a perspective view of our improved thill coupled to an axle-tree. Fig. 2 is a sectional view of the same. Fig. 3 is a view of a modification of the shaft-bow.

Like letters refer to similar parts on each figure.

25 The usual way of coupling thills is to secure them by connections to the front of the axle. Our invention relates specially to a rear coupling.

A represents the clip or band, which passes 30 round the axle, and has two extending ears, C, slotted so as to receive the bolt c. These ears C extend from each side at the back of the clip A, the intervening space serving as a clamp to hold the elastic block D.

35 A' is the base-bar of the clip A, held up against the under part of the axle in the usual manner by nuts screwed onto the forks of the clip A.

E is the thill-iron, which grasps the shaft or pole F in front. The thill-iron E, after following the shape of the shaft or pole at the upper part a required distance, is bent at the top upward, and is then bent until it reaches the point X, where it has an inward-projecting shoulder, through which an eye is formed. From thence it is again curved and bent downward until it reaches the lower bar, which follows the shape of the under part of the pole or shaft, and the two forward parts of the thill-iron are finally connected with the pole or shaft

by bolts f f, or in any suitable manner. Thus a continuous bow or guard, E', is formed by bending over the thill-iron, constructed as described, rearwardly.

Between the ears C C we place an elastic 55 block, D, the lower part of which rests on the base-bar A', and the upper part projecting above the clamping-ears C.

We do not claim, broadly, an elastic block as an anti-rattler, as this has been used before, 60 but not shaped, located, held in position, or operated as in our device.

The anti-rattling block in the devices generally in use is always clamped in the front part of the clip, in which case it is more liable to wear away than if placed at the back of the clip-bow, as provided in our device.

The elastic block is usually made of rubber, and, in fact, this is the only material known to be suitable, as fully described in the reissued Letters Patent No. 2,358, dated September 18, 1866, granted to William S. Chapman.

In Chapman's device, and all others similarly adjusted, the oscillation of the shaft or pole has also the effect to knead the rubber, 75 change its condition, and impair its normal elasticity. It becomes stiffened and hardened by the continual movements of the bearings

of the shaft or pole impinging against the ordinary elastic block. Moreover, the grit and 80 dust grind down or are forced into the mass of the block. We obviate these serious objections by the peculiar location, adjustment, and operation of our anti-rattling block D.

In the first place the base-bar A' can be lengthened so as to be a resting-place for the whole lower part of the block D. This base-bar A', whether of the full length of the width of the lower part of the block D or not, offers a plane 85 of resistance when the block is pressed down upon it, and causes it to spring upward.

An elastic cushion is thus provided which forms an under spring bearing for the whole coupling device. The same is the case with that part of the block D that projects upwardly above the jaws 95 of the clamping-ears C, this part of the block impinging against the inner side of the bow E'. In other words, the upper and lower parts of the elastic block D, pressing against firm resisting-surfaces, form a double-action spring. 100

We show only a quadrangular block, but do not desire to be understood as confining ourselves to this shape, as it is obvious that great advantages can be had by making it conform exteriorly to the configuration of the parts against which it is brought in contact—as, for instance, instead of being straight at the top, as shown in the drawings, it may be finished to follow the form of the inner surface 10 of the bow E'.

To more fully explain our invention in this respect, so that it may be clearly understood, one of the material features of this part of our device is, that our elastic block shall be subjected only 15 to pressure, and not to friction, and that this pressure shall be against the block rearwardly. The clip A having been secured to the axle by nuts *bb*, and the block D having been placed in position between the ears C, the bow E' is 20 passed over the end of the axle, the slotted projection being brought between the eyes of the ears C, and the two parts are then connected together by means of the bolt *c*, thus forming a hinged joint.

We prefer to make the bow E' of one continuous piece; but for some purposes it may have a hinged section, as shown in Fig. 3, as a modification. 25

It is manifest that a pole or shaft connected

as described cannot be projected either upward or downward but a given distance, as the hinge will only operate about a half-turn, the upper or the lower end of the bow E' being stopped by coming in contact with the clip B.

It is apparent that certain immaterial changes 35 and mechanical modifications of this invention may be made without departing from its scope.

Having now fully described our invention, what we claim is—

1. A thill for vehicles, coupled, by means 40 substantially as described, to the rear of the axle.

2. A thill having a rearwardly-projecting bow, E', supplied with locking-eyes, substantially as described. 45

3. In a thill-coupling, the bow E', surrounding the axle, in combination with the clip A, having extending ears C, which clamp the elastic block D when the whole device is 50 coupled to the rear of the axle, substantially as described.
